Des. 203,492
Patented Jan. 11, 1966

203,492

TOY MOTOR

Gerard J. Nault, Cumberland, R.I., assignor to Rosbro
Plastics Corporation, Pawtucket, R.I., a corporation of
Rhode Island

Filed May 10, 1965, Ser. No. 85,188

Term of patent 7 years

(Cl. D90—1)

FIG. 1

FIG. 2

FIG. 3

FIG. 4

FIG. 5

FIG. 6

FIG. 1 is a front elevational view of a toy motor, showing my new design;

FIG. 2 is a right-hand end view thereof;

FIG. 3 is a left-hand end view thereof;

FIG. 4 is a rear elevational view thereof;

FIG. 5 is a top plan view thereof; and

FIG. 6 is a bottom plan view thereof.

I claim:

The ornamental design for a toy motor, substantially as shown.
